DEVICE FOR USE IN APPLYING PRESSURE
TO SHOE BOTTOMS

Eliot M. Wadsworth, Wenham, Mass., assignor to
United Shoe Machinery Corporation, Flemington, N. J., a corporation of New Jersey

Application February 5, 1941, Serial No. 377,530

10 Claims. (Cl. 12—33)

This invention relates to devices for use in applying pressure to soles and shoes and more particularly to means for relatively positioning soles and shoes prior to the application of pressure thereto, and it is illustrated herein as embodied in a pad box for cement attaching soles to shoe bottoms.

Many pad boxes for use in cement attaching soles to shoes are provided with positioning means such as gages for locating the sole and shoe relatively to each other on the pad of the pad box before the sole attaching pressure is applied.

An important object of the present invention is to provide improved gages of the type referred to which are particularly adapted for use when the sole and shoe are to be attached to each other by a pressure responsive cement which causes adhesion immediately upon contact.

To this end the invention provides a gage for locating an end portion of a sole on the pad, and another gage for locating the corresponding end portion of a shoe relatively to the sole. In accordance with a feature of the invention, means is provided for holding the end portion of the shoe out of engagement with the end portion of the sole after they have been positioned relatively to each other by the gages and until pressure is applied to the sole and shoe. As herein illustrated, the means referred to preferably comprises a thin flat plate arranged to extend between the sole and shoe and thereby prevent them from sticking to each other by reason of the cement on their attaching surfaces. This plate, as illustrated, is carried by the sole and shoe gages, preferably by the shoe gage, and it is so arranged that it will move into position over the end portion of a sole on the pad without striking the sole.

In accordance with further features of the invention, the plate is so thin in cross section that the shoe may be located by the shoe gage in substantially its final or attaching position relatively to the sole, and the plate is provided with polished surfaces which prevent the tacky cement on the sole and shoe from causing these members to stick to the plate and which also prevent the plate from interfering with the cement as the plate is removed. Moreover, the arrangement is preferably such that the plate will be withdrawn from between the end portions of the sole and shoe upon the application of a part of the pressure to be applied thereto, thereby permitting these end portions to become firmly attached to each other by the cement thereon under the full sole attaching pressure.

With the above and other objects and features in view, the invention will now be described in connection with the accompanying drawing and will thereafter be pointed out in the claims.

In the drawing,
Fig. 1 is a plan view of gages embodying the present invention;

Fig. 2 is a section taken on the longitudinal median line of the gages and including a portion of the sole receiving pad with the toe ends of a sole and shoe indicated in broken lines;

Fig. 3 is a side elevation of the shoe and sole with the sole resting on the pad and the shoe suspended above the sole in a manner which might cause an error in relatively positioning the sole and shoe;

Fig. 4 is an enlarged view of the toe ends of the sole and shoe illustrating more clearly the error which might occur when the shoe is suspended above the sole;

Fig. 5 is a side elevation of the shoe and sole illustrating how the shoe may be positioned relatively to the sole with the aid of the gages of the present invention; and

Fig. 6 is a view similar to Fig. 5 after pressure has been applied to the sole and shoe and the gages have been withdrawn to inoperative position.

The sole and shoe locating gages of the present invention are illustrated as applied to a pad box for use in a cement sole attaching machine of the type disclosed in United States Letters Patent No. 2,047,185, granted July 14, 1936, upon an application filed in the name of Milton H. Ballard et al. The sole and shoe gages per se, however, as herein illustrated, are of the type disclosed in Letters Patent of the United States No. 2,262,759, granted November 18, 1941, on the application of Sidney J. Finn.

As disclosed in the Finn patent, the sole and shoe locating gages at the toe end of the pad box comprise a forked member 20 each arm of which has a pair of downwardly projecting ears 40 22 (Fig. 2) to which a pair of plates 24, 26 are pivoted by a pin 28 so that the free edges of these plates rest by gravity against a pad cover 30 overlying a pad 31 contained in the pad box. The plates 24, 26 on the opposite arms of the forked member 20 have their free edges located substantially at right angles to each other and constitute a V-gage which will engage and locate the toe end of a sole on the pad when the plates or gages are brought against the sole. The forked member 20 is carried by a slide 34 arranged for movement relatively to the sole in the direction of the longitudinal median line of its forepart and, in order that the plates 24, 26, while resting upon the pad cover 30, may have a limited amount of upward movement in response to the distortion of the pad by pressure of the sole and shoe against it, the slide 34 has a depending projection 35 (Fig. 2) which rests upon the cover 30 and limits downward movement of the slide

and prevents contact of the plates 24, 26 with an overlying shoe gage.

The shoe gage for locating the toe end of the shoe comprises a forked member 112 provided with two shoe engaging surfaces 113 located at approximately right angles to each other to form a V-gage. The surfaces 113 have considerable heightwise extent in a direction perpendicular to the surface of the pad 31 and these surfaces are substantially parallel to the inner or free edges of the sole gage plates 24, 26. Consequently, these surfaces 113 slant or incline toward the toe end of the pad from their upper to their lower edges.

As disclosed in the Finn patent, the V-gage 112 for the shoe is adjustably connected by a screw 114 to a slide 116 mounted on the slide 34 for longitudinal movement parallel thereto, the slide 116 being held on the slide 34 by a screw 118 passing through a slot in the slide 116 and threaded into the slide 34, as shown in Figs. 1 and 2. Moreover, the shoe V-gage 112 is arranged for adjustment laterally of the shoe and relatively to the sole V-gage 24, 26 by means of a transverse groove and tongue arrangement (not shown) between the V-gage 112 and the slide 116.

In the operation of these two gages, as disclosed in the Finn patent, the proper lateral and longitudinal adjustments are first made between the sole V-gage 24, 26 and the shoe V-gage 112, and the gages are then caused to move inwardly or rearwardly of the pad toward the toe end of a sole O thereon through the operation of mechanism provided on the cement sole attaching machine for that purpose, this movement continuing until the sole gage 24, 26 "finds" the toe end of the sole on the pad whereupon the toe gages become locked against movement away from the sole so that the shoe V-gage 112 is then in position to locate the toe end of a shoe S, on a last L, in proper relation to the toe end of the sole O.

The heel end of the sole, as disclosed in the Finn patent, is located on the pad by a sole gage consisting of a tongue 226 carried by a pivoted member (not shown) arranged to swing heightwise of the pad about a transverse axis so that the tongue can be swung into and out of engagement with the pad, the tongue being normally forced downwardly against the pad by a compression spring acting upon the pivoted member. The tongue 226 carries at its forward end a downwardly projecting pin 236 (Fig. 3) adapted to engage a hole formed in the sole centrally of its heel portion. The tongue is swung upwardly from the pad by a lever or handle (not shown) and, through an arrangement of slides and other mechanisms fully disclosed in the Finn patent, the tongue may be moved forwardly into position to engage the hole in the sole and locate the heel end thereof laterally and longitudinally of the pad. Upon release of the handle the sole gage 226 becomes locked against movement rearwardly or away from the sole.

The heel end of the shoe is located relatively to the sole by a V-gage 248 having a square shank or stem 250 which is bored longitudinally, as shown in Fig. 5, to receive a compression spring 260 which urges the gage yieldingly in a direction toward the shoe. The stem 250 is slotted at 254 to receive a transverse pin 256 about which the stem can pivot heightwise of the pad, the compression spring 260 bearing against this pin 256 and against a cotter pin at the front end of the gage. The stem 250 is normally held in an up- 75

wardly tilted position by a leaf spring 264 but the gage may be swung downwardly by the pressure or friction of the shoe against it, as shown in Figs. 3, 5 and 6. Since the rear gages 226 and 248 for relatively locating the heel ends of the sole and shoe form no part of the present invention, a more detailed description of them will not be necessary herein.

In placing the shoe S in the shoe gage 112, 248 above the sole O, which has been positioned on the pad by the sole gages 24, 26 and 226, the heel end of the shoe is seated in the V-gage 248 and the shoe and V-gage are moved rearwardly against the tension of the spring 260 until the toe end of the shoe can enter the shoe V-gage 112. As stated above, the inclined surfaces 113 of the gage 112 have sufficient heightwise extent perpendicular to the surface of the pad and parallel to the edge faces of the sole gage 24, 26, so that 15 the shoe may, if desired, be located by said surfaces in position to engage the sole while the forepart of the shoe is held out of contact with the sole, the shoe being suspended above the sole by the pressure of the V-gage 248 toward the 20 V-gage 112, as indicated somewhat diagrammatically in Figs. 3 and 5.

Suspending the shoe above the sole in this manner greatly facilitates the positioning operation, for example, when the sole is to be attached to the 30 shoe by a pressure responsive cement which sticks immediately upon contact, such, for example, as the polymerized chloroprene cement disclosed in United States Letters Patent No. 2,061,296, granted November 17, 1936, in the name of W. H. Wedger. However, while the above procedure is advantageous in some kinds of work, particularly when it is desired to bring the shank portion of the sole into engagement with the shoe before any substantial pressure is applied by 35 bulging the sole upwardly away from the pad, as disclosed in the Finn patent, nevertheless, in cases where the shank portions of the sole and shoe are not to be brought together in such initial contact, care must be used in placing the shoe 40 in the shoe gages without letting it touch the sole at any point and this has the effect of slowing up the positioning operation. Moreover, although the bulging of the shank portion of the sole in the manner indicated above insures the proper positioning of the shoe relatively to the sole because the initial contact of the members at the shank portion precludes any error as the shoe and sole are brought together throughout the rest of their attaching surfaces, it has been found in practice, 45 nevertheless, that, in cases where the sole is not initially bulged at the shank portion, an error is apt to occur in relatively positioning the sole and shoe if the shoe is suspended above the sole, unless considerable care is used in applying the sole attaching pressure, which is applied vertically, and also unless the forward pressure of the shoe V-gage 248 under the spring 260 is always sufficient to maintain the toe end of the shoe in 50 engagement with the inclined surfaces 113 of the V-gage 112 as the shoe descends under the action of the pressure applying abutments of the cement sole attaching machine, these abutments being indicated in the drawings by the numerals 314 and 316 and being arranged respectively to engage the last L and the forepart of the shoe S. In other words, the toe end of the shoe should 55 remain in engagement with the inclined surfaces 113 as the shoe descends in order that the toe end of the shoe be located accurately with respect to the toe end of the sole. Therefore, if the sole

attaching pressure of the machine is applied too rapidly in a vertical direction, or if the tension of the spring 260 becomes too weak to hold the shoe against the surfaces 113, there is a possibility that the shoe will leave the surfaces 113 and descend toward the sole in a more or less vertical direction with the result that the toe end of the shoe (and therefore the entire shoe) will be located too far rearwardly with respect to the outsole.

The error which might occur under such circumstances is illustrated diagrammatically in Figs. 3 and 4, the broken line A representing the path which the toe end of the shoe should follow as it descends in order to be correctly positioned relatively to the sole, and the broken line B indicating the path that the toe end of the shoe might follow if for any reason the shoe does not remain in engagement with the inclined surfaces 113 of the V-gage 112. It will be seen from the figures referred to that the possible error at the toe ends of the sole and shoe might under some conditions be serious enough to spoil the shoe if it were suspended high enough above the sole when placing the shoe in the V-gages 112 and 248.

In order to eliminate all possibility of an error of this nature occurring when relatively positioning the sole and shoe, and yet to retain the obvious advantages of holding the bottom of the shoe out of engagement with the outsole until pressure is applied, particularly when a pressure responsive sole attaching cement is used that sticks immediately upon contact, such as the polymerized chloroprene cement referred to above, the present invention provides means for holding the toe end of the shoe S out of engagement with the toe end of the sole O until pressure is applied to the shoe and sole by the pressure applying abutments 314, 316 of the cement sole attaching machine.

The means for accomplishing this purpose, as herein illustrated, comprises a substantially flat plate 120 of metal or other suitable material secured in any usual or convenient manner, as by brazing or welding, to the bottom edge faces of the forked portions of the shoe V-gage 112 which provide the shoe engaging surfaces 113. The plate 120, as shown in Figs. 1 and 2, is extremely thin in cross section and spans the space between the surfaces 113 for at least half their length, so that it covers a substantial area between said forked portions. The plate 120, moreover, is provided with polished surfaces which render it substantially immune to the adhesive action of the pressure responsive cement.

In operation, the sole and shoe gages at the toe end of the pad are moved inwardly as usual into engagement with the outsole O on the pad, the outsole having pressure responsive cement applied to the marginal portion of its attaching surface. The plate 120, being carried by the shoe V-gage 112, is located high enough above the surface of the pad to pass over the outsole without touching it as the sole V-gage 24, 26 "finds" the toe end of the outsole. After the sole is located on the pad and is engaged by the V-gage 24, 26, the shoe S, also having pressure responsive cement on its lower or attaching surface, is presented to the shoe gages as described above, that is, the heel portion of the shoe is placed by the operator in the shoe V-gage 248 and the shoe and V-gage are moved rearwardly against the pressure exerted by the compression spring 260 until the toe end of the shoe can be lowered into the shoe V-gage 112. However, the operator need not be careful during this op-

eration not to lower the toe end of the shoe too far in the shoe V-gage 112 so that it will engage the toe end of the sole, but he may lower it at once until it engages the plate 120, which now extends between the shoe and sole, as shown in Fig. 5. In this way he immediately insures that the toe end of the shoe S will be located properly with respect to the toe end of the outsole because these end portions will now be located substantially in their final or attaching positions with only the thin plate 120 extending between them. The plate 120, of course, prevents the toe end of the shoe from sticking to the toe end of the outsole because it extends between these portions and covers the pressure responsive cement on their attaching surfaces. However, since the plate is provided with polished surfaces, it does not adhere to or otherwise interfere with the cement on these surfaces.

The heel end of the shoe may now be swung downwardly about a pivot formed by the toe end of the shoe located in the shoe gage 112 to bring the entire shoe bottom into engagement with the sole except for the portions between which the plate 120 extends. Alternatively, the heel end of the shoe may, if desired, be held by the shoe V-gage 248 away from the sole until pressure is applied, as shown in Fig. 5, thereby permitting the shoe to be suspended above the outsole except for the portion engaging the plate 120, which, of course, cannot become attached to the outsole until the plate 120 is removed.

Before the full sole attaching pressure is applied, it is necessary to remove the plate 120 from between the shoe and sole in order that their toe portions may become cement attached to each other. This may be accomplished by automatically withdrawing the sole and shoe gages at the toe end of the pad to their inoperative positions by gage retracting mechanism, for example, of the type disclosed in Letters Patent of the United States No. 2,117,396 granted May 17, 1938, on the application of Sidney J. Finn. As illustrated in the patent last referred to, this gage retracting mechanism is fluid pressure controlled and is connected with the same source of fluid pressure supply as the power operated mechanism for operating the pressure applying abutments of the sole attaching machine. Accordingly, when the pressure against the sole and the shoe reaches a predetermined amount, preferably only enough to clamp the sole and shoe on the pad and thereby insure against their relative displacement, the gage retracting mechanism operates automatically to withdraw the toe gages 24, 26 and 112 and the plate 120 to their inoperative or retracted positions relatively to the pad. Since the pressure against the sole and shoe is relatively light at this time, the plate 120 can be readily withdrawn from between the toe ends of the sole and shoe. Moreover, as stated above, since the surfaces of the plate are polished they do not interfere with the cement on the attaching surfaces of the sole and shoe and, accordingly, when the full pressure is applied, the toe ends of the sole and shoe will become just as firmly attached to each other as the other portions of the sole and shoe.

By the use of the present invention, therefore, all possibility of an error occurring when locating the shoe and sole relatively to each other on the pad of the sole attaching machine will be eliminated and, in addition, the act of presenting the shoe to the shoe gages will be greatly facilitated in that it can be performed with less care on the

part of the operator and much faster than heretofore.

Having described my invention, what I claim as new and desire to secure by Letters Patent of the United States is:

1. A pad box for use in applying pressure to shoe bottoms having, in combination, a sole receiving pad, a gage for locating an end portion of a sole on the pad, another gage for positioning the corresponding end portion of a shoe relatively to the sole, and means arranged to engage the shoe and sole and to hold the end portion of the shoe out of engagement with the sole before pressure is applied to the sole and shoe but to permit said engagement when pressure is applied.

2. A pad box for use in applying pressure to shoe bottoms having, in combination, a pad for receiving a sole and shoe having adhesive on their attaching surfaces, gages for positioning the sole and shoe relatively to each other on the pad, and means for holding the shoe out of engagement with the sole until pressure is applied to the sole and shoe, thereby preventing the sole and shoe from sticking to each other before they have been properly positioned, said means being movable to permit the shoe to come into engagement with the sole after pressure is applied to the sole and shoe.

3. A pad box for use in applying pressure to shoe bottoms having, in combination, a sole receiving pad, a V-gage for positioning the toe end of a sole on the pad, a second V-gage for positioning the toe end of a shoe relatively to the sole, and means arranged to extend between the sole and shoe for holding the shoe out of engagement with the sole until after they have been positioned, said means being also arranged to move out from between the sole and shoe when pressure is applied to said sole and shoe.

4. A pad box for use in applying pressure to shoe bottoms having, in combination, a sole receiving pad, a gage for locating an end portion of a sole on the pad, a gage for locating the corresponding end portion of a shoe relatively to the sole, a plate arranged to extend between the sole and shoe for holding said end portion of the shoe out of engagement with the sole until pressure is applied to the sole and shoe, and means for withdrawing said plate from between the sole and shoe upon the application of said pressure.

5. A pad box for use in applying pressure to shoe bottoms having, in combination, a sole receiving pad, gages for relatively positioning the toe ends of a sole and shoe on the pad, said gages being movable into and out of operative position, and means carried by said gages for holding the shoe out of engagement with the sole until pressure is applied to the sole and shoe, said means moving out of operative position with the gages upon the application of said pressure.

6. A pad box for use in applying pressure to shoe bottoms having, in combination, a pad for receiving a sole and shoe having pressure responsive cement on their attaching surfaces, a V-gage for locating the toe end of the sole on the pad, a second V-gage for locating the toe end of the shoe relatively to the sole, said gages being movable longitudinally of the pad into operative position and being retractable into inoperative position upon the application of pressure to the sole and shoe, and means carried by said gages and movable into and out of operative position therewith for holding the toe end of the shoe out of engagement with the corresponding end of the

sole until pressure is applied to the sole and shoe.

7. A pad box for use in applying pressure to shoe bottoms having, in combination, a pad for receiving a sole and shoe having pressure responsive cement on their attaching surfaces, a V-gage for locating one end of the sole on the pad, a second V-gage for locating the corresponding end of the shoe relatively to the sole, said second V-gage having a considerable heightwise extent perpendicular to the surface of the pad, and means carried by said second V-gage for holding the end of the shoe out of engagement with the sole until pressure is applied thereto, thereby preventing the sole and shoe from sticking together before they have been properly positioned by the gages, said means being arranged to be withdrawn to inoperative position upon the application of pressure to the sole and shoe.

8. A pad box for use in applying pressure to shoe bottoms having, in combination, a pad for receiving a sole and shoe having pressure responsive cement on their attaching surfaces, a gage for finding one end of the sole after it has been placed on the pad, a second gage for positioning the corresponding end portion of the shoe relatively to the sole, and a thin plate extending between the sole and shoe for permitting said end portion of the shoe to be placed in substantially its final position relatively to the end of the sole without becoming stuck to the sole by the cement on said attaching surfaces, said plate being arranged to remain between the sole and shoe only until pressure is applied thereto.

9. A pad box for use in applying pressure to shoe bottoms having, in combination, a pad for receiving a sole and shoe having pressure responsive cement on their attaching surfaces, a V-gage for locating the toe end of the sole on the pad, a second V-gage for locating the toe end of the shoe above the sole and in position to be pressed downwardly thereagainst, said second gage having considerable heightwise extent perpendicular to the surface of the pad, and a plate arranged to extend between the sole and shoe and hold the toe end of the shoe out of engagement with the sole until pressure is applied, said plate being so thin that the toe end of the shoe may be placed in substantially its final position above the sole without danger of sticking thereto, said plate also having polished surfaces thereon which prevent the cement on the sole and shoe from sticking to the plate.

10. A pad box for use in applying pressure to shoe bottoms having, in combination, a pad for receiving a sole and shoe having tacky cement on their attaching surfaces, a V-gage for locating the toe end of the sole on the pad, a second V-gage for locating the toe end of the shoe above the sole, said second V-gage having a considerable heightwise extent perpendicular to the surface of the pad, and a plate carried by said second V-gage at the bottom thereof for engaging the toe end of the shoe as it is placed in the gage and holding said toe end out of engagement with the sole until pressure is applied, thereby preventing the toe end of the shoe from sticking to the sole before they have been properly positioned relatively to each other, said plate being so arranged that the toe end of the shoe may be placed in substantially its final position relatively to the sole and being also arranged to be withdrawn from between the sole and shoe upon the application of pressure thereto without interfering with the cement on said sole and shoe.

ELIOT M. WADSWORTH.
